UNITED STATES PATENT OFFICE

2,401,652

MACHINE FOR ASSEMBLING BAR PINS

Isador Mizrach, Brooklyn, N. Y., assignor to Pritt Novelty Co., Inc., New York, N. Y., a corporation of New York

Application August 17, 1944, Serial No. 549,913

2 Claims. (Cl. 153—1)

1

This invention relates generally to a bead forming press or machine for the manufacture of war service ribbon bars or any other type of insignia-bearing ribbons, but more specifically to a press wherein successive operations after the ribbon is applied manually to a channel bar, are effected by the same machine elements.

The main object of the invention resides in the provision of a press to clamp ribbons between a channel bar and a plate. Where the plate is not provided with a pin element for securing the service bar to a garment, the press also serves to clamp a pin plate between the aforementioned plate and the channel side walls.

A press of the above nature is especially adapted to assemble ribbon bars in conjunction with certain manual operations. For example, a service ribbon or other type of ribbon-bearing insignia is manually folded around a channel bar and then inserted within the press which performs a number of folding and pressing operations at the channel side walls by preferably hand manipulation of an operating lever. The press effects a line of fold of the ribbon adjacent the longitudinal edges of the channel bar at the same time inclining the covered side walls of the channel bar slightly for hand insertion of a plate against the resiliency of the said side walls for maintaining the ribbon between the plate and the channel side walls. Thereafter the press further inclines the walls for clamping the ribbon permanently between the plate and the channel side walls. Where the plate is provided with an attachment pin, the press inclines the side walls to a maximum position forming inner beads. However, where the plate is used merely for clamping purposes a pin plate is manually inserted over the clamping plate and the press is further manipulated for final and maximum inclination of the covered walls of the channel over the pin plate resulting in the formation of the final product.

A further object of the invention resides in the provision of a press which is easy to operate, compact, light in weight, economical to manufacture and which performs consecutive operations for the formation of a service ribbon bar comprised of a service ribbon, a channel, a clamping plate with a detaching pin or in the alternative a clamping plate without a detaching pin and a pin plate.

Another object of the invention resides in the provision of a press of the above nature which is capable of producing an increased number of service ribbon bars per unit of time.

These objects and other incidental ends and

2

advantages of the invention will hereinafter appear in the progress of the disclosure and as pointed out in the appended claims.

Accompanying this specification are drawings showing a preferred form of the invention wherein corresponding reference characters designate corresponding parts throughout the several views and wherein:

Figure 1 is a view in perspective of the press.

Figure 2 is a view in perspective of a channel bar on which the service ribbon is mounted.

Figure 2a is a view in perspective of a clamping plate.

Figure 3 is a view in perspective of a pin plate.

Figure 4 is an end elevation of a completed service ribbon bar formed by the press.

Figure 5 is a top plan view of the press shown in Figure 1.

Figure 6 is an end view in elevation of the press.

Figure 7 is a view in perspective of one of the compression rods for the channel side walls of the service ribbon bar.

Figure 8 is a sectional view of Figure 7 along the plane 8—8 thereof.

Figure 9 is a top plan view of the press partly in section.

Figure 10 is a sectional view of Figure 9 along the broken plane 10—10 in Figure 9 showing the press elements in intermediate and non-compression condition.

Figure 11 is a transverse sectional view of some of the press elements showing the open position of the press for the insertion of a channel bar therein.

Figure 12 is a view similar to Figure 11 showing the press elements in maximum compression.

Figure 13 is a transverse sectional view of the press showing certain elements in a position preliminary to folding the ribbon about the longitudinal edges of a channel bar.

Figure 14 shows the position of the press elements after having effected a folding of the ribbon and a slight folding of the side walls of the channel bar.

Figure 15 shows the press elements in maximum extended position preparatory to inserting against the resiliency of inclined side walls of the channel a clamping plate which is adapted to clamp the folded edges of the ribbon against the inner faces of inclined side walls of the channel.

Figure 16 shows the open position of the machine elements after the service bar has been manufactured.

Figure 17 shows the position of the press ele-

ments in final compression including a pin plate mounted on the clamping plate.

In accordance with the invention and the preferred form shown numeral 10 of the press indicates a table or base plate therefor on which are mounted a pair of spaced elongated blocks 11 and 12. Each of the blocks is provided with supporting angles 13 and 14 respectively which are affixed to the base plate 10 at the horizontal arms thereof by means of screws 15 and 16 respectively.

Between the bottom walls of blocks 13 and 14 and the upper face of plate 10 is a spacing or channel 17 while at the inner walls adjacent the top of blocks 11 and 12 are semi-cylindrical recesses 18 and 19. A pair of similar compression rods 20 and 21 are provided for partial rotation within the recesses 18 and 19, the said rods being mounted in end plates 22 and 23 at reduced end or nipple portions 24 and 25 respectively. End plates 22 and 23 are secured to the end walls of blocks 11 and 12 by suitable means such as screws 26 and 27.

Each of the compression rods is provided with an elongated channel as best shown in Figure 7 and indicated by numeral 20a and 21a respectively said channels having curved side walls 20b and 21b respectively. One end 24 of rod 20 is provided with a hand lever 28 at a semi-cylindrical end portion 28a said lever being secured thereto by means of a spline 29 as best shown in Figures 1, 5 and 9. The semi-cylindrical end 28a is provided with a series of gear teeth 30 which are adapted to mesh with gear teeth 31 at a portion of the circumference of a wheel 32 secured to one of the ends 25 of compression rod 21, said wheel being secured to end 25 by means of a spline 33.

An elongated supporting member 34 having a flat top and inwardly beveled side walls 35 and 36 is provided intermediate the inner side walls of blocks 11 and 12 and below the upper faces thereof as best shown in Figures 9 and 12 and serves as the support of the channel bar and the other elements during compression of the channel side walls by the compression rods 20 and 21 during operation and as will hereinafter appear. Depending from the lower wall of supporting member 34 are bushings 37 and 38 which cooperate with a plate 39 secured within channel 17 and against the lower walls of blocks 11 and 12 as by screws 40 as best shown in Figure 10. Plate 39 permits vertical reciprocal movement of supporting member 34 but prevents longitudinal movement by the utilization of inner studs 41 and 42 for bushings 37 and 38. Each of the inner studs projects through an opening in plate 39 and terminates in a screw head 43 of larger diameter than each of said openings in plate 39, the screw heads 43 entering in lowermost position openings 44 in base plate 10. The press above described is adapted to integrate bar channel 45, service ribbon 46, base plate 47 and plate 48 carrying the conventional pin, swivel and keeper. In using the press, channel 45 with cloth 46 folded therearound is inserted on supporting member 34 as shown in Figure 13 while the upper curved sides 20b and 21b of the compression rods 20 and 21 are in maximum separated position, the lower walls 20b and 21b supporting member 34 at the bottom wall. For this position lever 28 is manually forced down to the maximum. Thereafter lever 28 is raised slowly to effectuate the position of rods 20 and 21 shown in Figure 14 in which

position the ribbon 46 is folded along the longitudinal edges of channel 45 together with the formation of a slight inclination of the side walls of the channel. In this position member 34 is supported on plate 39 by ends of bushings 37 and 38. The folding of the ribbon 46 and inclination of the side walls 45 are effected by the channel portions 20a and 21a of the compression rods 20 and 21. Thereafter lever 28 is depressed downwardly to the maximum position and the channel bar 45 and ribbon 46 assume the position with respect to the press elements shown in Figure 15. At this time clamping plate 47 may be inserted over the ends of ribbons 46 and forced against the resiliency of the inclined side walls of channel 45 causing a tightening of ribbon 46 about the outer face of channel 45. When clamping plate 47 is not provided with an attaching pin, lever 28 is raised to a limited extent to further compress the inclined walls of channel 45 thereby securing clamping plate 47 therebetween. If, on the other hand, plate 47 is provided with an attaching pin, then lever 28 is drawn upwardly to a maximum position completing the final inclination of the side walls of channel 45 toward the formation of the final ribbon bar after which the lever 28 is depressed to the maximum to permit withdrawal of the final product.

Where a pin plate 48 is used to superpose plates 47 after the latter has been clamped by limited upward motion of lever 28 such a plate 48 which is somewhat narrower than plate 47 is forced between the inclined side walls covered by ribbon 46 until it sets on plate 47. Thereafter lever 28 is raised from the limited upward position to maximum upward position as best shown in Figure 17 as the final step in the production of a ribbon bar. Thereafter the lever 28 is forced to downward maximum position as shown in Figure 16 for the withdrawal of the final product.

I wish it understood that minor changes and variations in the location, shape, size and integration of parts may all be resorted to without departing from the spirit of the invention and the scope of the appended claims.

I claim:

1. A press to assemble ribbon bar pins from service ribbons, channel bars and plates whereby the several elements may be clamped about the channel bar at different compressed positions of the channel bar side walls, comprising a pair of spaced and opposite jaws, means to mount said jaws for mutual and opposite rotation, a vertically reciprocable supporting plate, means to mount said plate intermediate said jaws for limited uppermost and lowermost position, said plate having means to receive the base of the channel bar when the jaws are in full open position, a flange on the lower edge of each jaw and means on the supporting plate cooperating with each other to gradually release for lowering of and to gradually raise the supporting plate when the jaws are moved from open to closed and from closed to open positions respectively, the variable closing of the jaws correspondingly effectuating an inclination of the channel bar side walls toward each other for purposes of folding the ribbon about the edges of the channel bar and for clamping plates of different widths under the inclined channel side walls to hold the service ribbon edges in place, and means to rotate said jaws for selected open and closed positions.

2. A press to assemble ribbon bar pins from service ribbons, channel bars and plates whereby

the several elements may be clamped about the channel bar at different compressed positions of the channel bar side walls, comprising a pair of spaced, rotatable and elongated jaws, means to mount said jaws for mutual and opposite rotation, an elongated and vertically reciprocable supporting plate, means to mount said plate intermediate said jaws for limited uppermost and lowermost position, said plate having means to receive the base of the channel bar when the jaws are in full open position, cooperating means carried by the jaws and by the supporting plate to effectuate

the lowering and raising of the supporting plate when the jaws are moved from open to closed and from closed to open positions respectively, the variable closing of the jaws correspondingly effectuating an inclination of the channel bar side walls toward each other for purposes of folding the ribbon about the edges of the channel bar and for clamping plates of different widths under the inclined channel side walls to hold the service ribbon edges in place, and means to rotate said jaws for selected open and closed position.

ISADOR MIZRACH.
